UNITED STATES PATENT OFFICE.

EDWARD C. PANNING AND FERDINAND A. ISERN, OF ELLINWOOD, KANSAS.

TWO-CYCLE MOTOR.

1,382,539.

Specification of Letters Patent. Patented June 21, 1921.

Application filed May 20, 1919. Serial No. 298,379.

To all whom it may concern:

Be it known that we, EDWARD C. PANNING and FERDINAND A. ISERN, citizens of the United States, residing at Ellinwood, in the county of Barton and State of Kansas, have invented certain new and useful Improvements in Two-Cycle Motors; and we do hereby declare the following to be a full, clear, and exact description of the invention, such as will enable others skilled in the art to which it appertains to make and use the same.

Our invention relates to improvements in internal combustion engines of the two-cycle type.

An important object of this invention is to provide a two-cycle motor having a charge chamber communicating with the combustion chamber and adapted for supplying fresh charges of gas immediately upon the exit of the spent gases from the explosion chamber.

A further object is to provide a two-cycle motor wherein the gases are fed directly into the combustion chamber thereby eliminating the passage of the gases through the crank case.

A further object is to provide a two-cycle motor which operates with a high degree of efficiency with a low grade fuel.

A further object is to provide a two-cycle engine which by reason of the charged chamber operating in conjunction with the combustion chamber will operate under a high compression.

A further object is to provide a motor of the character described which is but few in parts of highly simplified construction and reliable in use.

A further object is to provide a motor of the character described especially adapted for use on tractors, trucks and other apparatus requiring a heavy duty motor.

A further object is to provide a two-cycle motor having means for closing the exhaust port of the working cylinder prior to the complete compression of the charge in the compression cylinder.

Other objects and advantages will be apparent during the course of the following description.

In the accompanying drawings forming a part of this application and in which like numerals are employed to designate like parts throughout the same,

Figure 1 is a section through a portion of a motor embodied in the invention,

Fig. 2 is a horizontal section taken on line 2—2 of Fig. 1,

Fig. 3 is a section through the motor 60 showing the power piston on the completion of a compression stroke,

Fig. 4 is a horizontal section taken on line 4—4 of Fig. 3,

Fig. 5 is a section on the line 5—5 of 65 Fig. 4,

Fig. 6 is a transverse section through the crank shaft, and

Fig. 7 is a fragmentary section through the motor, showing one of the valves arranged vertically.

In the drawings wherein for the purpose of illustration is shown the preferred embodiment of the invention, the numeral 10 designates the combustion cylinder of the motor provided with an exhaust port 11 in one side. A piston 12 is mounted in the cylinder and is connected with a crank shaft 13 by a connecting rod 14.

Coöoperating with the explosion or combustion cylinder 10 is a charge forming cylinder 15 having a piston 16 mounted therein and which for the purpose of this description will be designated a charge piston. The charge piston is also connected to the crank shaft by a connecting rod 17.

As illustrated in Fig. 2, the charge chamber A is in communication with the combustion chamber B by a transverse passage 18.

The upper portions of the chambers A and B are provided with laterally extending openings 19 and 20 respectively opening out through opposite sides of the motor.

The openings 19 and 20 are screw threaded 95 for engagement with valves generally designated by the numeral 21. The valves 21 are of the check valve type and include an exteriorly screw threaded base member 22 having a polygonal head 23 on its outer side for being engaged by a suitable wrench to remove the valve. As illustrated in Figs. 2 and 4, the valves may be readily removed for cleaning and removing the carbon from the cylinders. A hollow stem 23 is formed integral with the base 22 and has its inner portion in threaded engagement with a valve seat 24. A valve 25 is mounted in the seat 24 and is provided with a stem 26 extending through guiding elements 27. A 110

coil spring 28 is arranged on the valve stem and is interposed between one of the guiding elements and a pin 29 carried by the stem. The coil spring 28 serves to normally retain the valve head 25 seated. The valve arranged in the top of each of the cylinders is surrounded by a supporting wall 30 open at its inner end to permit of the free passage of the gases. As illustrated in Fig. 2, 10 the valve in the top of the charge cylinder 15 controls communication between the charge cylinder and a fuel supply passage 31. During the downward movement of the charge piston 16, the valve within the charge cylinder A is drawn inwardly thereby permitting of the passage of gases into the charged cylinder through apertures 32 in the valve sleeve. On its upward movement the charge piston 16 forces the gas vapor 15 through the passage 18 into the combustion chamber 12. The charge enters the combustion chamber B through the valve in the top of the combustion chamber. During the upward movement of the charge piston 20 25 16 the power piston 12 is on its power stroke and upon reaching its lowermost position the spent gases are expelled through the port 11. Upon the passage of the spent gases from the chamber B the new gases pass 30 35 in from the chamber A. Subsequently the power piston 12 starts on its compression stroke upwardly while the charge piston 16 starts on its intake stroke thereby preparing a new charge for the combustion chamber B. 40 45 50 As illustrated in Fig. 1, the charge piston is retarded slightly to permit the working cylinder to close the exhaust port before the charge piston reaches upper dead center. At the time the gas in the charge cylinder 40 is most highly compressed the exhaust port is closed and the unignited gases thereby prevented from escaping. The retarding of the charge cylinder is accomplished by offsetting the throw of the crank shaft having 45 connection with the piston rod 17.

In the form of our invention shown in Fig. 7, we have disposed the valve in the working cylinder vertically whereby the bore of the working cylinder may be reduced.

By having the valve disposed vertically, the diameter of the working cylinder may be made much smaller, owing to the fact that said valve will not occupy as much space as when disposed horizontally.

The ignition may be from a magneto, battery or by high compression. When a sparking system is employed a spark plug 33 is provided for the combustion chamber B 60 at a point adjacent the inlet valve.

In the practice of our invention the inventive idea may be carried out either in a motor of the vertical, horizontal or horizontal opposed type. Any desired number of explosive cylinders may be employed.

If desired, the charge cylinder 15 may be employed exclusively for supplying air to the combustion chamber while a separate fuel pump supplies liquid fuel to the combustion chamber. When it is desired to ignite the compressed gases by compression, 70 the charge chamber A is increased in size with relation to the combustion chamber B, thereby forcing a greater and more highly compressed charge into the combustion 75 chamber.

While we have shown the preferred embodiment of our invention, it is understood that such minor changes in arrangement and construction of parts may be made as will 80 remain within the spirit of the invention and the scope of the appended claims.

Having thus described our invention, what we claim is:—

1. A two-cycle motor comprising a block 85 having combustion and charge forming cylinders, a head for said cylinders having combustion and charge forming chambers, one of the ends of said chambers communicating with the combustion and charge forming 90 cylinders respectively and their other ends opening outwardly through the head, bases threaded in said chambers closing the last named ends thereof, check valves carried by said bases for controlling the passage of fuel 95 through the chambers, said chambers communicating with each other between the valves, said charge forming chamber having an intake port, and working and charge forming pistons in the combustion and 100 charge forming cylinders respectively.

2. A two-cycle motor comprising a block having combustion and charge forming cylinders, a head for said cylinders having combustion and charge forming chambers 105 therein, one of the ends of said chambers communicating with the combustion and charge forming cylinders respectively and their other ends opening outwardly through the head, bases threaded in said chambers 110 and closing the last named ends thereof, hollow shanks formed on said bases and having flared and perforated ends adapted to engage the walls of said chambers, valve seats in said flared ends of the shanks, stems 115 formed on the valves and slidable in the shanks, tension means in said shanks for the stems, said chambers communicating with each other between the valves, said charge forming chamber having an intake port, and 120 working and charge forming pistons in the combustion and charge forming cylinders respectively.

In testimony whereof we affix our signatures in presence of two witnesses.

EDWARD C. PANNING.
FERDINAND A. ISERN.
